UNITED STATES PATENT OFFICE.

PIERRE BASMAISON, OF SAN FRANCISCO, CALIFORNIA.

EXTENSION-BIT.

1,401,455.

Specification of Letters Patent.

Patented Dec. 27, 1921.

Application filed November 9, 1920. Serial No. 422,852.

To all whom it may concern:

Be it known that I, PIERRE BASMAISON, a citizen of the United States, and resident of San Francisco, county of San Francisco, State of California, have invented a new and useful Extension-Bit, of which the following is a specification.

This invention relates to improvements in extension bits, and has for one of its objects the provision of means for increasing the strength of the bit and so reinforce the cutters that the bit will not stick even if the brace is not held steady.

Another object is to provide ample clearance for the shavings to prevent them from rolling up and blocking the passage of the bit in the channel.

Another object is to provide a bit that may be easily sharpened with a flat file.

Another object is to provide a clamp for holding the two parts of the bit rigidly together, and one that is easily adjusted and that may be held very close to the center of the tool.

Another object is to make a clamp adapted to hold bits of various thicknesses.

Another object is to provide a clamp for adjusting and holding the radial rod very rigidly without leaving any marks on the rod.

Another object is to provide a yielding center for the tool and means for making said center rigid so that it may be used to punch a center hole.

Another object is to provide a gage for indicating when the brace is not held true, and also provide other uses for the gage such as glass cutting.

Another object is the provision of a spring for holding the yielding center out, and a limit stop for said center, and means for replacing the yielding center with a bit or pin, and means for clamping them securely in any adjusted position.

Another object is to provide a plate to hold the center point from digging into the material to be cut, and a further object is to provide means for setting the cutting bit at different angles to the perpendicular brace for boring tapered holes and cutting tapered plugs.

Other objects will appear to those skilled in the art, as the description proceeds.

An embodiment of the invention is shown in the accompanying drawing in which similar numerals refer to similar parts

throughout the several views, and in which—

Figure 1 is a side elevation of the extension bit.

Fig. 2 is an end elevation looking from the left of Fig. 1.

Fig. 3 is a plan view with parts broken away for purpose of illustration.

Fig. 4 is a view of the clamp head, looking from the right of Fig. 1.

Fig. 5 is a view of the yielding center pin showing the groove and stop in same.

Fig. 6 is a detail of the clamping means for holding the radial rod.

Fig. 7 is a bottom view of the post showing a detail of the yielding center pin lock.

Fig. 8 is a side elevation of the extension bit for cutting a taper hole or plug by means of the angle attachment.

Fig. 9 is an end view of the angle attachment.

Fig. 10 shows how the extension bit can be set to cut tapers of different angles.

Fig. 11 is a view looking at the rounded surface of the bit, with the cutting bit and limit gage together.

Fig. 12 is an edge view looking from the right of Fig. 11.

Fig. 13 is a view looking at the back or flat surface of the bit.

Fig. 14 is a view of the bottom portion of the limit gage and side cutter.

Fig. 15 is an enlarged view showing a portion of the cutting bit including depth cutter and side cutter.

Fig. 16 is a bottom view of Fig. 15.

Fig. 17 is a plan view of a center plate.

Fig. 18 is a sectional view of same.

Fig. 19 is a top view of Fig. 11.

The numeral (1) indicates a post provided with a shank (2) adapted to fit the chuck of a brace or other tool. Slidably mounted in the post is the radial rod (3), on the end of which is fixed the clamp head (4) which is adapted to hold the limit gage (5), and the cutting bit (6) firmly together and in the seat by means of the bolt (7), the thumb nut (8), and the head (9) which has a cut away bevel edge (10) which acts against the bevel edge of the limit stop (5) to force it back in the seat, and sidewise against the member (6) which has a bevel edge (11) fitting the bevel in the seat. The limit gage (5) has a longitudinal groove (12) in which the longitudinal tongue (13) fits. The cutting bit (6) has a depth cutting

edge (14) and a side cutter (15). The groove (16) is of a size to give ample clearance for the shavings. The limit gage (5) has a side cutter (17), a bearing surface (17') and a cut away portion (18) which allows clearance for the shavings. The radial rod (3) has a V-shaped groove (19) and is held in the desired radial adjustment by a pin (20) in the post (1). The end of the pin is V-shaped to fit the groove, a taper hole (21) is provided through the pin transversely, a thumb screw (22) is so mounted that its taper portion (23) will engage the bottom of the taper hole and force the pin (20) down and clamp the radial rod rigidly. At the end of the taper (23) a straight portion is provided and fits into a hole of the same size to take some of the strain off the screw threads of (22). The yielding center consists preferably of a round pin (24), with a point (25), and is adapted to slide into a hole in the post (1) as shown by the dotted lines at (26). A spring (27) which hooks over a pin (28), and engages notches (29) in the post tends to hold the yielding center pin out. A groove (30) is provided in the pin. A thumb screw (32) with a point (33) fits into the groove (30), and is adjusted so the pin (24) can slide freely, the action of the spring holding the stop pin (31) against the screw point (33). The screw (32) is held securely by the lock-nut (32'). Means for locking the yielding center pin so it can be used for a punch is provided by having a lever (34) pivoted at (35) so the edge will swing into a transverse slot (36) in the pin (24). The lever being of spring material a slight projection (37) which hooks over the corner of the post 40 in the locked position and slides on the bottom in the free position holds the lever in the two positions. A boring gage (38) is mounted in the head (4); this gage is so designed that it can be held rigidly by the thumb screw (39), or it can be held by friction of a spring (40), the tension of which is adjusted by the screw (41). A glass cutter (42) is mounted in the end of the gage which can be used by reversing the gage. 50 The turned up portion (43) can be used to make a rabbet. A center plate (44) has sharp points (45) around the edge, and a centering piece (46) may be used when the hole made by the center point is undesirable. 55 For cutting taper holes or plugs with the extension bit, an attachment for setting the post at various angles is shown in Figs. 8 and 9, and consists of an auxiliary shank (47), adapted to fit the chuck of a brace, an extension (48) with a suitable clamp (49) for attaching to the shank (2) of post (1), and a connecting link (50) pivoted at (51) and (52). In order to keep the shank (47) and brace in a vertical line with the point 60 (25), a side bar (53) is provided on the link (50) at (54). The ends of the bar are provided with slots (55) and (56) adapted to slide on the thumb screw (57) in the extension (48), and on the screw (58) in the shank (47), the thumb screws being capable 70 of clamping the bar rigidly in any position. When the thumb screws are loosened the link (50) is free to swing in the arc of a circle A, and tilt the extension (48) with the post (1) at an angle to the vertical line B 75 with the point (25) touching said line, and thus the cutting bit is set to cut a circular groove (59) tapering toward the center line; while if the link is made to swing in the opposite direction the cutting bit is set to cut 80 a circular groove (60) tapering away from the center line as shown in Fig. 10. In operation the shank (2) is clamped in the chuck of a brace, the limit gage (5) and cutting bit (6) are placed together and clamped 85 in the seat at the required height in the head (4) by means of the screw (7), thumb nut (8) and clamping head (9), then the radial rod (3) is moved to set the cutting bit at the required radius of the circle to be cut, and 90 is clamped in place by means of the thumb screw (22) which forces the pin (20) into the groove (19) as described. Now in order to make a center hole, the yielding center is made rigid by throwing the lever (34) so its 95 edge enters the slot (36), then the center pin can be used as a punch to make a suitable hole. The brace being perpendicular, the gage (38) is adjusted to touch the surface of the material to be cut, the thumb screw (39) loosened, and the spring (40) set at the required tension; if the gage touches evenly all around as the brace is turned, it indicates that the brace is held in the proper position. For cutting glass the gage (38) 100 is reversed and held in position by the thumb screw (39), a center is provided by the plate (44) using a strip of rubber or the like under the plate on the glass. 105

My claims are as follows, but various modifications may be made in the above described form within the scope of my invention.

I claim:

1. An extension bit comprising a rotatable post, a radial rod slidable through said post, clamping means for said rod, a center pin adapted to telescope into said post longitudinally, a transverse slot in said pin, a pivoted lever on said post, one edge of said lever being adapted to slide into said slot and hold said pin rigidly for the purpose described. 115
2. In an extension bit comprising a rotatable post with a shank adapted to receive the chuck of a brace or like tool, a spring extended center pin adapted to telescope into said post longitudinally, a limit stop for said center pin, a radial rod adapted to slide through said post transversely, means for clamping said rod and said post together, a 120
3. In an extension bit comprising a rotatable post with a shank adapted to receive the chuck of a brace or like tool, a spring extended center pin adapted to telescope into said post longitudinally, a limit stop for said center pin, a radial rod adapted to slide through said post transversely, means for clamping said rod and said post together, a 125
4. In an extension bit comprising a rotatable post with a shank adapted to receive the chuck of a brace or like tool, a spring extended center pin adapted to telescope into said post longitudinally, a limit stop for said center pin, a radial rod adapted to slide through said post transversely, means for clamping said rod and said post together, a 130

head on said rod, a seat for a cutting bit in said head, means for clamping said bit to said head, a gage rod adapted to slide through said head parallel with said bit, 5 rigid means and spring means adapted to be selectively used for holding the gage in a desired position.

3. An extension bit, comprising a rotatable post, an adjustable transverse rod in said post, a tool holder on said rod, an extension to said post, an auxiliary shank, a connecting link, one end of which is pivoted on said

shank and the other end pivoted on said extension, a side bar pivoted on said link, one end of said bar being slotted and connected 15 to said shank by means of a screw through said slot, the other end being slotted and connected to said extension by means of a screw through said slot, the said screws being adapted to clamp said side bar firmly to said shank and said extension and thereby holding said link at any adjusted angle.

PIERRE BASMAISON.
